(57) **CLAIM**

The ornamental design for a linear indirect asymmetric light fixture, as shown and described herein.

DESCRIPTION

FIG. 1 is a front perspective view of a lighting fixture according to an embodiment of the present invention.

FIG. 2 is a right end elevation view of a lighting fixture according to an embodiment of the present invention, with the left end of the lighting fixture being a mirror image.

FIG. 3 is a front elevation view of a lighting fixture according to an embodiment of the present invention.

FIG. 4 is a top elevation view of a lighting fixture according to an embodiment of the present invention with the opposite side being a mirror image.

FIG. 5 is a bottom elevation view of a lighting fixture according to an embodiment of the present invention.

FIG. 6 is a rear elevation view of a lighting fixture according to an embodiment of the present invention; and,

FIG. 7 is a perspective view of a lighting fixture according to an embodiment of the present invention.

Elements of the fixtures in FIGS. 1-7 are in broken lines to illustrate portions of the linear indirect asymmetric light fixture that form no part of the claimed design.

The break lines in FIG. 7 indicate that the appearance of any portion of the liner indirect asymmetric light fixture between the break lines forms no part of the claimed design.

1 Claim, 3 Drawing Sheets
